UNITED STATES PATENT OFFICE

HERMAN ADLER, OF BERKELEY, CALIFORNIA

COMBINED SHELF AND ROBE RAIL

Application filed February 15, 1932. Serial No. 593,058.

This invention is a combined shelf and robe rail or towel bar and has special reference to a device to be installed on the rear of the front seat of an automotive vehicle, whereby a folding shelf is provided as also a suitable robe rail. The device is similarly applicable to use in bath rooms providing a folding shelf and towel bar.

In the usual automotive vehicle no place is provided where glasses, cups and other utensils may be safely set while eating lunches or in other cases where a place is desired to deposit articles which must be maintained in a certain position.

It is for such purposes that the present invention was evolved.

The main object of the invention therefore is to provide a folding shelf for automotive vehicles.

Another object of the invention is to provide a combined shelf and robe rail or towel bar in which the weight of the rail or bar will retain the shelf in folded position, and in which resilient or frictional means retains the shelf in operative position, the rail functioning as a retainer for the folded shelf.

A still further object of the invention is to provide a shelf of the folding type with adjusting means whereby the operative angle of the shelf may be varied relative to the supporting surface.

Other objects and advantages of the invention will become apparent as the following description is read on the drawing forming a part of this specification and in which similar reference characters are used to indicate similar parts throughout the several views, of which:

Fig. 1 is a rear elevation of the front seat of an automotive vehicle with my invention installed thereon.

Fig. 2 is a side elevation of Fig. 1.

Fig. 3 shows the invention in folded position.

Fig. 4 is an end elevation of the invention in operative position.

Fig. 5 is an end elevation of Fig. 3, Figs. 4 and 5 being drawn to an enlarged scale.

The invention consists primarily of a pair of brackets secured to the back of the seat

of an automotive vehicle, arms hingedly connected at one end to the brackets, a shelf having the opposite ends hingedly connected intermediate the front and rear edges to the other end of the arms, a robe rail spanning the rear end of the shelf and pivotally connected thereto, the pivots cooperating with stops which are provided with protuberances to resiliently or frictionally engage the pivots, whereby the shelf is retained in operative position by the protuberances, and retained in folded position by the weight of the robe rail.

The brackets 10 are formed with a pair of ears 11 provided with a pivot 12 to hingedly support the arms 13, the brackets being secured to a wall or seat by means of bolts or screws 14.

A shelf 15 is pivotally secured at its opposite ends, intermediate the front and back edges to the other end of arms 13 as indicated at 16. This shelf is preferably supported at a point intermediate the rear edge and the center of the shelf whereby the lever arm is greater on the forward portion than on the rear.

Pivotally secured adjacent the rear edge of the shelf, in spanning relation is a robe rail 17 which is formed at right angles at each end to substantially broad U form, the legs of which terminate in eyes 18, which cooperate with the pivots or pins 19 which extend exteriorly of the eyes as indicated at 20, to cooperate with stops 21, and are adapted to be frictionally engaged by a tongue 22 made of resilient material or provided with a protuberance 23, and integral with stops 21.

Stops 21 are preferably slotted as at 24 to adjustably cooperate with screws 25 which may be provided with thumb nuts although in ordinary use, the stops will be adjusted to the desired position and be retained in this position.

Fig. 4 shows the stops adjusted to retain the shelf in horizontal position, while Fig. 2 shows the stops adjusted to retain the shelf in inclined position.

By this arrangement, a shelf is provided which is adapted to various purposes though

primarily intended for use in automotive vehicles, to replace the usual robe rail, is also ideally adapted to bath room use, and as the stops are adjustable the shelf is readily adjusted to suit the requirements of both, the mounting surface and the angle of inclination of the shelf relative to the mounting surface.

The shelf when folded back is retained in folded position by the robe rail.

Having described an operative device it will be understood that variations in construction and arrangement of parts which are consistent with the appended claims may be resorted to without detracting from the spirit or scope of the invention or sacrificing any of the advantages thereof.

I claim:

1. A combined folding shelf and robe rail comprising a pair of pivotally mounted supporting arms, a shelf supported rearwardly of the transverse center and at its opposite ends by said arms, a robe rail pivotally secured rearwardly of said arms and adapted to normally retain said shelf in inoperative position by the weight thereof, and stop elements adapted to retain said shelf in operative position.

2. A combined folding shelf and robe rail comprising a shelf hingedly supported at its opposite ends by a pair of arms intermediate disposed between the transverse center and rearward edge of the shelf, a robe rail spanning said shelf and pivotally secured rearwardly of the supporting points of said arms whereby said robe rail is adapted to normally retain said shelf in inoperative position, engaging elements on said shelf, and stop elements adjustably mounted and adapted to cooperate with said engaging elements for retaining said shelf in operative position.

3. In combination, a shelf, a link pivotally secured to each end of the shelf rearwardly of the center of gravity, a robe rail longitudinally spanning the shelf and pivotally secured adjacent the rearward edge of the shelf and means for frictionally retaining the shelf in operative position against the weight of the robe rail.

4. In combination, a shelf, a link for each end of the shelf and pivotally secured at one end to said shelf rearwardly of the center of gravity and a bracket pivotally secured to the other end of each link, a robe rail spanning the shelf and pivotally secured at each end adjacent the rearward edge of the shelf, and means for frictionally retaining the shelf in operative position.

In testimony whereof I affix my signature.
HERMAN ADLER.
